UNITED STATES PATENT OFFICE.

CHARLES SCOTT-SNELL, OF WESTMINSTER, LONDON, ENGLAND, AS-SIGNOR TO AIR LIGHT COMPANY LIMITED, OF WESTMINSTER, LONDON, ENGLAND.

INCANDESCENT GAS-LIGHTING.

No. 801,618.

Specification of Letters Patent.

Patented Oct. 10, 1905.

Application filed December 29, 1904. Serial No. 238,865.

To all whom it may concern:

Be it known that I, CHARLES SCOTT-SNELL, a subject of the King of Great Britain and Ireland, residing at 51 Victoria street, Westminster, in the county of Middlesex, England, have invented certain new and useful Improvements in and Relating to Incandescent Gas-Lighting, of which the following is a specification.

- 10 The invention relates to what is known as "intensified gas-lighting." Intensified gas-lighting is obtained at present mainly by supplying gas under pressure to incandescent gas-burners, so that an increased supply of air is drawn into the burner. Thus a more completely combustible mixture is obtained which will burn with a more intense flame at the burner-head, so that the incandescent mantle reaches a higher temperature and the illuminating value of a given area of mantle is greatly increased over what can be obtained with ordinary chimney-draft. It has also been proposed to obtain this additional supply of air to each burner by almost completely inclosing the burner and employing a long chimney to draw practically a completely combustible mixture of gas and air through the burner. It has also been proposed to employ air under considerable pressure distributed to a series 30 of burners, the gas and air supplies being controlled by means of cocks to give the proper proportion for combustible mixture. To obtain the gas or air under pressure for a distribution system, it has been hitherto proposed 35 to employ gas or air compressing apparatus which will produce some considerable pressure, supplying either or both gas and air at pressures always exceeding the normal gas-pressure supply of two or three inches of 40 water-column and generally at least eight inches of water-column.

Now the object of this invention is to obtain this intensified gas-lighting with simpler means than have hitherto been employed.

- 45 The invention consists in a system comprising a number of burners, each burner being supplied with gas and with air under a relatively very small pressure through a comparatively large conduit of small resistance, such 50 air-supply being obtained conveniently from a fan driven by a suitable motor, preferably an electric motor. The several branches from the conduit connecting to the burners are also

of large bore and arranged without taps or the like, so that the resistance of the conduit 55 and its branches is practically the same, whether burners are in use or not.

Only the gas-supply is controlled by taps and no mixture takes place except in the burner-mixing-tube, although the whole air 60 passing through the burners for combustion is supplied from the air-trunk. This system is of great value in flour-mills or dusty warehouses where the burners at present tend to choke very badly. The supply of air for the 65 burners can be drawn by the fan from the outside of the building and supplied by way of the large air-trunk to the burners.

Referring to the accompanying drawings, Figure 1 is a diagrammatic plan view of one 70 modification of the system, Figs. 2 and 3 being elevations showing diagrammatically two arrangements of the burners.

In carrying the invention into effect according to the modification shown in Fig. 1 75 a large air-trunk *a* is provided capable of passing air to supply a series of burners under small pressure. One-tenth to one-fiftieth of an inch of water-column is found to be sufficient. On the other end of this trunk a fan 80 *c* is provided, preferably working in a ring or hood and driven by a small electric motor *d*. Onto the air-trunk are attached the various branches *b*, carrying the burners. These branches are also of relatively large bore, and 85 burner-heads *f* are provided on the burners. A gas-service pipe *g* is also arranged with branches *h*, supplying a gas-jet *i* at each burner.

A moderate length of pipe *e* is preferably 90 provided, Fig. 2, which will act as a mixing-tube for the burner-head. Each burner-head *f* is arranged with a non-lighting back top and is made with passages of sufficient capacity to offer no substantial resistance to the 95 air-supply. The fan is thus able to supply a considerable number of burners, as the energy it is required to give out for even a large air-supply is relatively small. Cocks are not provided on the air branches *b*. The lights are 100 allowed to be put out by turning off the gas at the cocks *j*, the air-supply blowing into the atmosphere when the burner is not lighted except when all the lights are extinguished, in which case the fan may be stopped. The 105 fan is therefore working against practically

a constant resistance and is thoroughly reliable.

In a large system several fans working each its own section may be installed in preference to a single fan doing all the work, or where a single fan is sufficient at one end of the air-duct a duplicate fan may be installed for emergencies at the other end, but until required having no connection with the air-duct *a*, *10* being separated therefrom by a damper or cut-off plate.

In distributing air for a large number of lights where the air-duct is required of large diameter this may be made of ornamental *15* section or in factories may conveniently be made of canvas or like material, preferably fireproofed.

Where the lights have to stand drafts or to burn in a foul atmosphere, the burner-tube *e*, *20* Fig. 3, is preferably surrounded with an additional tube *l*, which is adapted to carry at its head an open-topped globe *n*. This outer tube *l* is jointed to the globe, so that the external atmosphere is not admitted, and *25* the supply of air from the trunk in addition to passing up through the burner-tube *e* passes also through the holes *m* in the bottom of the tube *e* and up between the tubes *e* and *l* and delivers a certain amount of air into the *30* space within the globe surrounding the mantle. The globe has thus always a certain amount of outflow, which renders the lantern practically draftproof. This lantern is in appearance very like an ordinary arc-lamp.

35 Having now particularly described and as-

certained the nature of my said invention and in what manner the same is to be performed, I declare that what I claim is—

1. In combination with a separate air-distribution system for intensified gas-lighting *40* in which an air-compressor delivers the air for combustion to a number of lamps, means for maintaining a constant load on the compressor consisting of distributing-ducts of low resistance and free from valve and cock *45* control, substantially as and for the purpose described.

2. An intensified gas-lighting system having in combination, a number of gas-burners, an air-trunk of comparatively large diameter *50* common thereto, a plurality of separate connecting branches free from cock control and arranged to supply the lamps in parallel, means for forcing a comparatively large volume of air at low pressure into said trunks, *55* and means for supplying gas to said lamps.

3. In an intensified gas-lighting system having a free and uninterrupted separate air-supply, means for maintaining a sufficient up-draft in the chimney to counteract external *60* drafts comprising a tube *l* arranged concentrically outside the burner-tube *e* and holes *m* connecting said outer tube with the air-supply.

In witness whereof I have hereunto set my hand in presence of two witnesses.

CHARLES SCOTT-SNELL.
